UNITED STATES PATENT OFFICE.

ARTHUR A. BYERLEIN, OF DETROIT, MICHIGAN.

PRESS.

Application filed September 20, 1924. Serial No. 738,940.

The present invention relates to apparatus for working metal and more particularly to a press.

One of the principal objects of the present invention is to provide a press having improved means for counter-balancing and adjusting the punch or slide member thereof.

Other objects of the invention will be apparent from the following description taken in connection with the accompanying drawings, in which

Fig. 1 is a front elevation of a press embodying the present invention;

Fig. 2 is a vertical section on the line 15 2-2 of Fig. 1;

Fig. 3 is a fragmentary sectional view showing the adjustable parts of the connecting rod;

Fig. 4 is a section on the line 4-4 of 20 Fig. 1;

Fig. 5 is a view taken on the line 5-5 of Fig. 1 showing the motor driven means for adjusting the length of the connecting rods;

Fig. 6 is a sectional view taken on the 25 line 6-6 of Fig. 5;

Fig. 7 is a fragmentary view similar to Fig. 1, showing a modified form of the invention; and

Fig. 8 is a vertical sectional view on the 30 line 8-8 of Fig. 7.

Referring to the drawings, the press consists of a frame or stationary part which comprises a bed portion 20, side frame members 21 and an arch member 22. The side frame members 21 are provided at 23 with guides for the reception of a punch or slide member 24 which is adapted to slide upwardly and downwardly in the guides 23. The slide member 24 is actuated by means 35 of suitable driving means which, as herein shown, includes a drive shaft 25 rotatably mounted in the frame, cranks 26 formed on the drive shaft and connecting rods or members 27 pivotally connected at 28 and 29 with the cranks 26 and the slide member 24 respectively.

As is usual with presses of the present type, the metal to be worked is placed between the bed 20 and the slide member 24, or rather between dies carried by these parts. The upper face of the bed 20 is, therefore, adapted to receive the lower die, and the lower face of the slide member 24 is so constructed that an upper die or punch may be secured thereto for movement with the

slide member. It will be understood that the movement or stroke of the slide member 24 depends upon the throw of the crank 26. Fig. 1 illustrates the extreme forward or 60 downward position of the slide member 24, that is, the nearest approach of the slide member to the bed at the bottom of the stroke. The distance between the slide member 24 and the bed 20 when in this position 65 may for convenience be termed the "shut height" and may be indicated by the reference character 30. It is frequently found desirable to change or adjust the shut height of a press owing to variations in different sets of dies made necessary by varying kinds of work, different thickness of metal employed, or for other reasons, and means is therefore provided in the present apparatus for quickly and easily effecting an adjustment of the shut height of the press.

Referring particularly to Figs. 1 and 3 it will be observed that each connecting rod 27 consists of an upper part 31 and a lower part 32, the upper part 31 being provided with a screw-threaded socket 33 which is adapted to receive the turnable screw-threaded bolt or connection screw 34 of the lower part 32. As shown in Fig. 3, the bolt 34 is provided with a head or flange portion 35 which is adapted to be received in the socket 36. A flanged sleeve or bushing 37 is secured to the lower part 32 of the connecting rod with its sleeve portion extending into the socket 36 and engaging 80 the flange or head 35 of the bolt in such a manner as to permit rotation of the screws 34 but to prevent any axial movement of the bolt 34 with reference to the part 32 of the connecting rod. To effect simultaneous adjustment of the two connecting rods 27, each of the screw-threaded screws 34 is provided with a beveled gear 38 keyed thereon, which gears may be driven from a common drive shaft 39 having a beveled pinion 40 at each end thereof for engagement with the bevel gears 38. The drive shaft 39 may be actuated or driven by suitable motor driven mechanism which is preferably carried by the connecting rods 27 and movable 105 in unison therewith. Brackets 41 secured to the lower parts 32 of the connecting rods 27 provide bearings for the driving shaft 39 and also constitute a support for the motor platform 42. The platform is supported from the brackets 41 upon connecting shafts or bars 44 the opposite ends of which 110

- are mounted within the brackets 41. As best shown in Figs. 5 and 6 the platform 41 carries an electric motor 46 and suitable gears for effecting driving connection between the motor and the shaft 39. While the driving connection may be of any suitable form it is herein shown as consisting of a gear train including gear 47 mounted on the motor shaft, gears 48, 49, 50, 51 and 52 suitably mounted upon the platform 42, and 53 mounted on the shaft 39. This gear train may be housed in a suitable housing (not shown) also carried upon the motor platform 42. This construction is such that great flexibility is secured since the parts for adjusting the connecting rods may be made standard except for the shafts. And by using shafts of varying lengths the standard adjusting mechanism parts may be applied to presses of varying sizes, in which the connecting members are spaced different distances apart. Also this construction permits of applying or removing the adjusting mechanism as a unit.
- For locking the parts of the connecting rods 27 in adjusted position, the upper part 31 of each connecting rod is provided with a flanged plug or clamp 54 the inner end of which is formed to conform to the wall of the bore or socket in the part 31 and is threaded similarly to said bore. This clamp is adapted to slide in a transverse passage or opening 55 formed in the wall of part 31 and opening into the threaded bore or socket thereof intermediate the ends of said socket. The plug 54 may by means of suitable clamping bolts 56 be forced against the connection screw 34 to lock the same against movement or rotation in its socket. In adjusting the length of the connecting rods the clamp 54 is first loosened, after which the electric motor 46 may be operated to rotate the connection screws 34 in their respective screw-threaded sockets 33 thereby simultaneously increasing or decreasing the length of the two connecting rods. After the connecting rods have been adjusted to the desired lengths the clamps 54 are drawn against the stems 34, the threads on the clamps registering with the threads on the stems to lock the same against rotation.
- The threads upon the inner end of the clamp preferably correspond to the threads in the socket 33. To secure such correspondence the threads on the clamp are formed at the same time as the thread is machined in the socket 33. To accomplish this the clamp is positioned within the passage 55 with a liner or collar in place between the flanged head of the clamp and the body of the member 31 which is of such thickness as to cause the inner curved end of the clamp to correspond with, and be in effect a continuation of, the wall of the socket 33. The part 31 and the clamp 54 are then machined together. The liner is then removed. This method of construction insures practically exact correspondence of the thread in the socket 33 and on the clamp 54. And the clamp is of such length that its flanged head is spaced from the part 31 a short distance so that drawing up on the bolts 56 will cause clamping of the threaded connection screw 34 relative to the part 31.
- A counter-balancing means is provided for the slide member 24, such counter-balancing means including a spring or other yielding means which is adapted to be placed under increased compression on the downward movement of the slide member and which thus assists the upward movement of the slide member. The counter-balancing mechanism consists of two brackets 60 mounted on the arch member 22 of the frame, each bracket pivotally supporting at 61 a bell crank lever having a forwardly extending arm 62 and a downwardly extending arm 63. The forwardly extending lever arms 62 are pivotally connected by means of links 70 with the connecting rods 27, each connecting rod being provided for this purpose with a lug carried by the upper part 31 thereof. The brackets 60 are provided with upwardly extending flanges 65 which form abutments for the cooperating coiled springs 66. Pivotedly connected with the lever arms 63 and extending forwardly therefrom through apertures 67 are rods 68 which carry at their forward ends adjustable heads or washers 69 which are adapted to engage the forward ends of the compression springs 66. The compression springs 66 are thus confined between the flanges 65 and the heads 69 of the rods 68, and the linkage is such that when the slide member 24 and the connecting rods 27 move downwardly or forwardly the springs 66 are increasingly compressed. Upon the up or rearward movement of the slide member 24, the springs 66 of course tend to expand and to assist the driving means in raising the slide member 24. It should be noted that the links 70 of the counter-balancing mechanism are thus connected so that the setting of the counter-balancing mechanism is entirely independent of adjustment changes in the connecting rod to effect variations in the shut height. An advantage of this arrangement is that the shut height of the press may be regulated quickly and easily as desired without in any way modifying the action of the counter-balancing means or requiring adjustment of the latter.
- Figs. 7 and 8 show a modified form of counter-balancing means in which the entire mechanism is positioned beneath the arch. This form of the invention functions just as does the form described above; but in this form the springs 80 are supported upon a bracket 81 secured on the rear of the arch

member 22. Pivoted to the bracket 81 at 82 is a lever 83 extending forwardly between the arch member 22 and the drive shaft 25, the forward end of the lever 83 being connected to the upper part of the connecting rod 27 by means of link 84. Pivotally connected with the lever 83 and extending upwardly through apertures 85 in bracket 81, are a pair of compression rods 86 having adjustable heads or washers 87 at their upper ends to engage the upper ends of compression springs 80. It will be perceived that the compression springs 80 are compressed on the downward or forward movement of the connecting rods 27 and that upon the upward movement of the connecting rods 27 the springs 80 expand and tend to assist the drive shaft 25 in raising the connecting rods and slide member carried thereby.

While the forms of apparatus herein described constitute preferred embodiments of the invention, it is to be understood that the invention is not limited to these precise forms of apparatus, and that changes may be made in either without departing from the scope of the invention which is defined in the appended claims.

What is claimed is:

1. In an apparatus of the character described adapted for working metal, a frame having therein a bed and a reciprocable slide arranged to receive therebetween the metal to be worked, driving means for sliding said slide downwardly towards the bed and for returning it upwardly, yielding means operatively connected to the slide and adapted to be placed under tension during the down-stroke of the slide and to assist the upward movement thereof, and means for adjusting the nearest approach of the slide to the bed at the bottom of the down stroke, said last-mentioned means having provisions for effecting said adjustment without affecting the adjustment or operation of said yielding means.

2. In an apparatus of the character described adapted for working metal, a frame having a slide member mounted for reciprocation forwardly and backwardly therein, a driving member mounted in said frame for moving the slide forwardly and backwardly, means for adjusting the extreme forward movement of the slide member with respect to the frame, said means including a plurality of pairs of cooperating screw-threaded parts and a common means for operating said parts simultaneously, and means adapted to be placed under tension during movement of the slide member in one direction and to assist movement of the slide member in the opposite direction, said last-mentioned means being connected to one of said members rearwardly of said adjusting means.

3. In an apparatus of the character de-

scribed adapted for working metal, a frame having a reciprocable slide member mounted therein, means for driving the slide member, said driving means including a connecting member connected with the slide member, means for adjusting the length of the connecting member, and counter-balancing means secured to the connecting member in such manner as to be unaffected by adjustment of said adjusting means.

4. In an apparatus of the character described adapted for working metal, a frame having a reciprocable slide member mounted therein, means for driving the slide member forwardly and rearwardly, said driving means including a drive shaft carried by the frame, and connecting means pivotally connected with the drive shaft and the slide member, adjusting means carried by the connecting means for adjusting the length of the same, and counter-balancing means secured to the connecting means rearwardly of said adjusting means, whereby to be unaffected by adjustment of said adjusting means.

5. In an apparatus of the character described adapted for working metal, a frame having a slide member mounted for reciprocation forwardly and rearwardly therein, means for driving the slide member forwardly and backwardly, said driving means including a drive shaft carried by the frame, and a plurality of connecting rods connected between the drive shaft and the slide member, means carried by said rods for adjusting the length of the connecting rods, and counter-balancing means secured to the connecting rods rearwardly of said adjusting means, whereby to be unaffected by adjustment of said adjusting means.

6. In an apparatus of the character described adapted for working metal, a frame having a slide member mounted for reciprocation forwardly and rearwardly therein, means for driving the slide member forwardly and rearwardly, said driving means including a drive shaft carried by the frame, and a plurality of connecting members connected between the drive shaft and the slide member, means carried by said connecting members for adjusting the length of the connecting members, and counter-balancing means secured to the connecting members rearwardly of said adjusting means.

7. In an apparatus of the character described for working metal, a frame having a slide member mounted therein, a drive shaft carried by the frame, a connecting rod connected between the drive shaft and the slide member, said connecting rod having cooperating relatively movable screw and socket members for adjusting the length of the connecting rod, and a separate clamp plug detachably carried in an opening in said socket member at a point removed from

the end of said socket member and adapted to be forced into locking engagement with said screw member.

8. In apparatus of the character described, which is provided with a frame, a slide member mounted therein, and a driving means; a connecting rod for connecting the driving means to the slide, comprising a member having a socket therein, and a transverse 5 passage extending through the said member and terminating within the socket therein intermediate its ends, a stem movably mounted in the socket, and a separate clamp block 10 slidingly guided within the said transverse 15 passage for locking the stem within the socket, the construction being such that the stem is supported throughout the extent thereof positioned within the socket irrespective of the locking means.

9. In an apparatus of the character described for working metal, a frame having a slide member mounted therein, a drive shaft carried by the frame, a plurality of connecting members for connecting said 20 drive shaft and said slide member, said connecting members including cooperating telescoping parts adapted to be operated to increase or decrease the length of the connecting members, and operating means movable 25 in unison with said connecting members for operating said parts, said operating means including an electric motor and a driving connection between the motor and said parts of each of said connecting members.

10. In an apparatus of the character described adapted for working metal, a frame having a reciprocable slide member mounted therein, a crank shaft carried by the frame, a pair of connecting rods connected directly 40 between the crank shaft and the slide member to have an angular movement at one end and a reciprocatory movement at the other end, and motor means for simultaneously adjusting the length of the connecting rods, said means being supported entirely 45 by said connecting rods and movable therewith.

11. In an apparatus of the character described adapted for working metal, a frame having a slide member mounted therein, a drive shaft carried by the frame, a pair of connecting members connected between the drive shaft and the slide member, and means for simultaneously adjusting the length of 50 the connecting members, said means including movable adjusting parts carried by said connecting members, a supporting platform carried by the connecting members, a motor carried by said platform, and a driving connection between the motor and said movable 55 adjusting parts.

12. In an apparatus of the character described adapted for working metal, a frame having a reciprocable slide member mounted 60 therein, a drive shaft carried by the frame,

a pair of connecting members connected between the drive shaft and the slide member, and means for simultaneously adjusting the length of the connecting members, said means including movable adjusting parts 70 carried by said connecting members, and a transverse driving shaft geared to both of said movable adjusting parts for actuating the latter, an electric motor supported by said connecting members, and a driving connection between said motor and said transverse driving shaft. 75

13. In apparatus of the character described, a frame, a slide mounted thereon, a drive shaft carried by the frame, a pair of connecting members connected between the drive shaft and the slide member, brackets on the connecting members, supporting shafts mounted therein, a platform detachably mounted on the shafts, means carried 80 by the brackets for varying the length of the connecting members, and a motor carried by the platform and in driving connection with the length varying means, the construction being such that the brackets and supported parts may be mounted upon or removed as a unit from, the connecting members. 85

14. In apparatus of the character described, a frame, a slide mounted thereon, a drive shaft carried by the frame, a pair of connecting members connected between the drive shaft and the slide member, detachable brackets mounted on the connecting members, supporting shafts removably mounted 90 in said brackets, a platform detachably mounted on said supporting shafts, a motor on said platform, an adjusting shaft mounted in the brackets and operatively connected to the connecting members to effect 95 adjustment thereof, and a gear train carried by the supporting members and effecting driving connection between the motor and the adjusting shaft, the construction being such that shafts of different lengths may 100 be used to fit varying spacing of the connecting members. 105

15. In a press of the class described adapted for working metal, a frame having a reciprocable slide mounted therein, a rotatable crank-shaft in said frame, an adjustable length connecting rod pivotally connected at one end to the slide and at its other end to the crank-shaft, adjusting means provided on said connecting rod for adjusting 110 the length of the same, and a counter-balancing spring adapted to store up energy during movement of the slide in one direction to assist movement of the slide in the other direction, connected to the connecting rod at one side of the adjusting means remote from the slide so as to be unaffected by adjustment of the said adjusting means. 115

16. In an apparatus of the character described, a frame, a slide mounted therein 120

for reciprocatory movement, a crank-shaft carried by said frame, a pair of connecting rods directly connected between the crank-shaft and the slide, said connecting rods being adjustable as to length to effect varying of the path of travel of said slide, a support detachably connected to both said connecting rods, and motor means comprising a motor and a gear train, detachably carried by said support for adjusting the length of said connecting rods, said motor means and said support being movable in unison with the angular movements of the connecting rods so that adjustment of the 15 length of the connecting rods is maintained constant during their angular movements.

17. In an apparatus of the character described, a frame, a reciprocal slide mounted therein, a crank-shaft carried by said frame, a pair of connecting rods directly connected between the crank-shaft and the slide to move angularly at the crank-shaft ends thereof and reciprocate at the slide ends thereof, said connecting rods being adjustable as to length to effect varying of the 20

path of travel of said slide during operation, a gear mounted upon each connecting rod, driving gears therefor also mounted upon said connecting rods, and motor driven mechanism mounted on said connecting rods 30 in constant driving relationship with said driving gears for effecting length adjustment of said connecting rods.

18. In an apparatus of the character described, a frame, a slide mounted therein for reciprocatory movement, a crank-shaft carried by the frame, a connecting rod connected to the crank-shaft and the slide, and comprising two threadedly connected telescopic sections, a driven gear mounted upon one section of said connecting rod, motor means for effecting length adjustment of said connecting rod carried by said one section to move in unison with its angular movements, and comprising a motor and a 40 drive gear in substantially constant meshing relationship with said driven gear.

In testimony whereof I hereto affix my signature.

ARTHUR A. BYERLEIN.
